UNITED STATES PATENT OFFICE

2,507,923

INTERNAL-COMBUSTION ENGINE

Donald W. Morris, North Hollywood, Calif., as-
signor to Morris Development Co., Los Angeles,
Calif., a copartnership

Application September 28, 1946, Serial No. 700,000

20 Claims. (Cl. 123—51)

1

This invention relates to engines of the opposed piston type, and more particularly to such engines in which the pistons are relatively angularly offset.

Typical of opposed piston types of engines is the type known in the art as the two crankshaft, diamond engine. This type engine is characterized by a pair of crank shafts usually extending horizontally one above the other. Angularly offset cylinders are disposed between the two crank shafts to form a diamond, with a crank shaft at each end of the long axis and a combustion chamber at each end of the short axis.

It is known in this type of engine, which is often of the Diesel type, to provide cylinders with cylinder liners which may be removed from the engine framework or block for servicing or replacing. In certain known types of engines it is necessary to remove the liners from the crank shaft, or rear, ends of the cylinders. This necessitates complete removal, or at least substantial displacement of each crank shaft, so that the liners may be removed past the crank shafts.

In certain other types of engines, the complete cylinder and head assembly must be removed as a unit, which necessitates that the sides of the framework or block be completely open, resulting in a structure which is not rigid and is bulky due to clearance required.

It is an object of this invention to provide a two crank shaft engine of the type having a plurality of pairs of cylinders disposed between the crank shafts, and so arranged that the cylinders may be removed without disturbing the crank shafts.

It is an object of this invention to provide a two crank shaft engine of the type having a plurality of pairs of cylinders disposed between the crank shafts, wherein the cylinders may be removed in a direction away from the respective crank shafts with which they are associated.

It is another object of this invention to provide a two crank shaft engine of the type having pairs of angularly displaced cylinders between the crank shafts removably supported in a frame, the head ends of each pair of cylinders being in adjacent relation, with an opening in the frame adjacent said head ends, through which the cylinders of each pair may be removed, and a removable closure for said opening.

It is another object of this invention to provide such an engine wherein the closure has a cylinder head forming portion adapted to be interposed between the adjacent ends of each

2

pair of cylinders, against which said cylinders seat.

It is another object of this invention to provide such a closure wherein the head portion 5 forms a common combustion chamber, establishing communication with the cylinders of each pair.

In the operation of an internal combustion engine, the numerous coacting parts of the engine 10 tend to change dimensions by expansion, from cold operation to hot operation. Furthermore, due to internal operating stresses, the relative dimensions of coacting parts often change. More specifically, such changes occur between a cylinder head and an abutting cylinder or cylinder liner.

It is another object of this invention to provide a joint between a cylinder head and a cylinder which is tight under all conditions of operation, and which is free to permit of minute 20 shifting required to adjust the joint to the various operating conditions encountered during the use of an engine.

More specifically, it is an object to provide such 25 a joint in which the juncture between cylinder head and cylinder is provided through complementary annular bevelled surfaces on the two abutting parts.

It is known to utilize in the cylinders of internal combustion engines a piston universally 30 mounted on the end of a connecting rod, whereby the piston is free to adjust itself to minute angular shifts between the cylinder and the crank shaft.

It is thus another object of this invention to 35 provide an engine having a universally mounted piston, in which the cylinder in which said piston reciprocates is mounted in such manner as to shift, and compensate for minute changes in engine dimensions due to the effects of temperature 40 expansion, wear, and internal stresses.

It is another object of this invention to provide improved exhaust passage forming means for an internal combustion engine having a plurality of cylinders disposed in side by side relation and having annular exhaust ports.

This invention possesses many other advantages, and has other objects which may be made more easily apparent from a consideration of one 50 embodiment of the invention. For this purpose there is shown a form in the drawings accompanying and forming part of the present specification. This form will now be described in detail, illustrating the general principles of the invention; but it is to be understood that this de-

tailed description is not to be taken in a limiting sense since the scope of the invention is best defined by the appended claims.

In the drawings:

Figure 1 is a sectional view taken transversely of a diamond type engine embodying the principles of this invention;

Figure 2 is an enlarged view similar to Figure 1, showing particularly the cylinder head and the abutting, angularly offset, opposed cylinders;

Figure 3 is a side view of the engine taken along line 3-3 of Figure 2 showing especially the external appearance of the removable cylinder head;

Figure 4 shows the clamping ring, or plate, serving to hold a cylinder against the cylinder head, the view being taken on line 4-4 of Figure 2;

Figure 5 is a view taken on line 5-5 of Figure 4, showing a cross section of the clamping ring including a cross section of the cylinder;

Figure 6 is a horizontal sectional view of the cylinder head taken along line 6-6 of Figure 2;

Figure 7 is an elevational view of the cylinder head alone, removed from the engine;

Figure 8 is an enlarged sectional view of the joint between a cylinder and the cylinder head; and

Figure 9 is a sectional view showing an alternative form of joint.

In Figure 1, 11 represents a diamond type engine having a frame or block providing cylinder receiving portions or frameworks 12, 13, 14 and 15. Within these portions 12-15 are included, respectively, cylinders 16, 17, 18 and 19. On each side of engine 11 are openings 21 and 22, respectively adjacent the outer ends of the portions 12, 13, 14 and 15 and the adjacent head ends of cylinders 16, 18 and 17, 19. Through these openings the cylinders 16-19 may be removed from the engine for servicing. When engine 11 is in use, openings 21 and 22 are closed by closure plates 23 and 24, having cylinder head portions 25 and 26, respectively, thereon extending into the engine. Cylinder head portions 25 and 26 have openings 27 and 28, respectively, therethrough communicating with the forward or head ends of the respective opposed cylinders with which they are associated.

A bottom crank shaft 31 carries, among others not shown, pistons 32 and 33 on the ends of connecting rods 34 and 35 respectively. Pistons 32 and 33 reciprocate in cylinders 18 and 19, respectively. The diamond-shaped configuration is completed by an upper crank shaft 36 having mounted thereon connecting rods 37 and 38 carrying pistons 39 and 41, which latter reciprocate in cylinders 16 and 17 respectively.

Intake air is supplied to engine 11 by way of top cylinders 16 and 17 through a series of ports 42 and 43 which are directed inwardly with a slight tangential component, whereby to impart a swirling motion to the intake air as it enters the cylinders. The series of ports 42 and 43 extend completely around the cylinders 16 and 17, respectively, and are supplied with air by longitudinally extending manifolds 42a and 43a.

Scavenging or exhaust is effected by way of bottom cylinders 18 and 19 through a series of ports 44 and 45 which extend around the cylinders 18 and 19 respectively. The series of ports 44 communicates with an annular space 44-a (Fig. 5) formed in the respective framework portion 14, which space 44-a in turn communicates with an exhaust chamber or passage 46 extending

longitudinally between the cylinders 16 and 18, as well as with an outside manifold or passage forming means 44-b. The inside chamber 46 also communicates in a similar manner with the series of ports 45, an outside manifold 45-b also being provided as before. By providing inside and outside manifolds, the size of the spaces as 44-a required for free exhaust of the spent gases is reduced, allowing the cylinders of each row to be closely spaced and reducing the overall length of the engine.

Referring now to Figure 2, an enlarged view of one of the obtuse, side corners of the diamond is shown illustrating particularly the unitary plate and cylinder head 23-25. This view illustrates a fuel injector 47 mounted in the center of plate portion 23 and supplied with fuel through pipe 48. In the conventional manner, air is compressed between pistons 32 and 39 within opening 27, which forms a combustion chamber. Upon injection of fuel from injector 47 combustion occurs, forcing the pistons apart.

In assembling the cylinders 16 and 18 and the head 25 into the engine, closure plate 23 is fitted over opening 21 with cylinder head portion 25 extending into the framework of engine 11. Dowel pins 49 serve to properly align plate 23 around opening 21, the anchoring thereof being effected through bolts 51 and 52. As shown in Figure 3, each of these bolts serves the dual function of holding two adjacent plates 23 to the engine frame by virtue of cooperating semicylindrical bores at the edge of each plate, two of which together form the complete bore for the bolts 51 and 52.

As best seen in Figures 2 and 7, cylinder head portion 25 of closure plate 23 has annular outer bevelled surfaces 53 and 54 adjacent respectively the ends of opening 27. Annular surface 53, representative also of surface 54, forms an outer bevelled seat, against which abuts the inner bevelled surface 55 on cylinder 16. The annular surfaces 53 and 55 are preferably formed at slightly different inclinations, so that when the cylinder 16 is seated against the head 25, a single line circular contact is provided. A metal to metal seal is thus provided which, by virtue of the different angle of the beveled surfaces 53 and 55, maintains its effectiveness throughout slight relative shifting between the cylinder 16 and the head 25.

For this purpose it may be desirable to make one or both of the surfaces curved about a point on the center line of the cylinder 16. Thus, in Figure 8, the surface 53 on the head forming portion 25 is shown as comprising a spherical zone, the annular surface 55 on the cylinder 16 being conical. Optionally, the abutting surface on the cylinder 16 may be formed as a spherical zone, the surface on the head forming portion 25 being conical, as shown in Figure 9.

To fortify this joint, an elastic sealing ring 57, fabricated preferably of heat resistant material, may be inset in one of the abutting surfaces, as for example in cylinder 16 adjacent head portion 25, being disposed preferably outside the metal-to-metal seal 56, in which position it is protected from the deleterious effect of hot combustion gases at the joint. Sealing ring 57 also serves to prevent water from the cooling jackets surrounding the cylinder 16 from penetrating to the metal-to-metal seal at 56.

To facilitate assembly and disassembly, and also in order to permit each cylinder, as 16, to adapt itself to seat 53 on cylinder head portion

25, the anchoring means for holding cylinder 16 against the seat is disposed at the opposite end of cylinder 16 from head portion 25. A typical arrangement is shown in Figure 5, wherein clamping ring 58 is illustrated, having an internal skirt portion 59 bearing against an annular flange 61 on cylinder 16. Clamping ring 58, as shown in Figure 4, is attached to the rear of framework 14 by means of four bolts 62. As shown in Figure 5, cylinder 16 may be forced against seat 54 of head portion 25 at any desired pressure, depending on the torsional force applied to bolts 62.

As mentioned hereinbefore, each cylinder-receiving portion of the frame, for example that indicated by the numeral 12, comprises rings 63 and 64 at the center and crank shaft and, respectively, thereof. In these openings are held ring portions 65 and 66 formed integrally on cylinder 16, the latter being of smaller diameter than the former to facilitate removal of cylinder 16 through opening 21, in a manner to be described. Sealing rings 67 and 68 serve to isolate the intake chamber defined between portions 63 and 64 of framework 12, and the cooling water chamber defined between portion 63 and the upper end of cylinder 16.

The skeleton-like construction of the frame portions 12 and 14, with opening 21, and the employment of the removable closure plate and cylinder head 23—25, permits of removal of each the cylinders 16 and 18 through the outer ends of the respective frame portions 12 and 14.

In removing the cylinders, clamping rings 58 are first taken off and the cylinders 16 and 18 forced down toward their respective crank shafts enough to clear the annular seats on cylinder head portion 25. After removal of the fuel injection supply system, including pipe 48, bolts 51 and 52 are removed, allowing closure plate 23 with its cylinder head portion 25 to be removed entirely from the frame of engine 11. One of the cylinders 16, for example, is then pushed forwardly within its framework. By virtue of the configuration of frame portion 12, and the small outer diameter of ring portion 66 on cylinder 16 compared to the inner diameter of ring 63 on frame portion 12, cylinder 16 may be skewed around sufficiently to be removed through opening 21. Cylinder 18 is removed in a similar manner. Replacement of the cylinders is effected by reversing the above procedure.

It will be noted in Figures 2 and 7 that opening 27 is flared at each end thereof, as shown, for example, at 71. This divergence of the walls of opening 27 permits of entry of the converging walls 72 of the corresponding piston 39, whereby the compression chamber is made more compact, allowing of better fuel distribution and hence better combustion, with attendant increase in engine efficiency. In operation, the flared, cooperative configuration of walls 71 and 72 causes a turbulence to be created in combustion chamber 27, as the remaining air is squeezed from the diminishing annular space between these walls by the advance of piston 39. This turbulence effectuates a more efficient combustion in the chamber. Turbulence is also effected by the slight tangency of inlet port 42 which imparts swirling to the air, as mentioned hereinbefore.

The universally adjustable seating of the cylinders on their respective seats readily adapts this construction to the employment of a universally connected piston. Such an arrangement is shown in Figure 2, wherein piston 32 has been cut away

to show at 73 a universal, or ball and socket, type of connection between piston 32 and its rod 34.

It is to be understood that the explanation set forth above concerning cylinder 16 applied equally to each of the cylinders 17, 18 and 19.

As will be noted by reference to Figures 6 and 7, circulation of coolant around the combustion chamber formed by opening 27 is effected by the provision of an annular cooling channel 74 immediately surrounding the chamber.

I claim:

1. A cylinder head for an opposed piston type internal combustion engine; comprising a plate adapted to fit over an opening in the engine adjacent the forward ends of opposed cylinders and to form a closure for the opening, a cylinder head portion on said plate extending therefrom into the engine and having an opening therethrough adapted to communicate between said forward ends of said cylinders and to form a combustion chamber, said opening having at each end thereof diverging walls, thereby adapting each end of said opening to receive the converging end walls of the head of a piston, and beveled, annular surfaces around the outer edge of said opening at each end thereof forming seats for opposed cylinders.

2. In an internal combustion engine having a pair of opposed cylinder-receiving portions, the combination of a separate, removable cylinder head fitting between said portions at the respective forward ends thereof and having an opening communicating between the forward ends of said portions and forming a combustion chamber, said head having, around the edge of each end of said opening, annular beveled surfaces adjacent said forward ends of said portion, forming cylinder seats, cylinders in each said portion having annular beveled surfaces complementary to the bevel of said seats and abutting said seats, one of said surfaces being of convex cross section, and means holding said cylinders against said seats.

3. An internal combustion engine having a framework defining two opposed angularly offset cylinder-receiving portions, the outer part of said framework adjacent the juxtaposed heads of said opposed cylinder-receiving portions having an opening therein large enough to pass a cylinder, a pair of cylinders held respectively in said cylinder-receiving portions of said framework, a closure plate closing said opening, a cylinder head portion on said closure plate extending into the engine and having an opening therethrough communicating between said cylinders and forming a combustion chamber, a first pair of annular, beveled surfaces, one around each end of said opening forming cylinder seats, a second pair of annular beveled surfaces, one on the end of each said cylinder abutting said seats, and means holding said cylinders against said seats.

4. An internal combustion engine having a framework defining two opposed angularly offset cylinder-receiving portions, the outer part of said framework adjacent the juxtaposed heads of said opposed cylinder-receiving portions having an opening therein large enough to pass a cylinder, a pair of cylinders held respectively in said cylinder-receiving portions of said framework, a closure plate closing said opening, a cylinder head portion on said closure plate extending into the engine and having an opening therethrough communicating between said cylinders and forming a combustion chamber, a first pair of annular, beveled surfaces, one around each end of said opening forming cylinder seats, a second pair of

annular beveled surfaces, one on the end of each said cylinder abutting said seats, one of said pairs of surfaces constituting an inner bevel, the other of said pairs of surfaces constituting an outer bevel, and means on the respective ends of said cylinders remote from said second pair of surfaces holding said cylinders against said seats.

5. An internal combustion engine having a framework defining two opposed angularly offset cylinder-receiving portions, the outer part of said framework adjacent the juxtaposed heads of said opposed cylinder-receiving portions having an opening therein large enough to pass a cylinder, a pair of cylinders held respectively in said cylinder-receiving portions of said framework, a closure plate closing said opening, a cylinder head portion on said closure plate extending into the engine and having an opening therethrough communicating between said cylinders and forming a combustion chamber, a first pair of annular, beveled surfaces, one around each end of said opening forming cylinder seats, a second pair of annular beveled surfaces, one on the end of each said liner abutting said seats, one of said pairs of surfaces constituting an inner bevel, the other of said pairs of surfaces constituting an outer bevel, and clamping rings around the respective ends of said cylinders remote from said second pair of surfaces holding said cylinders against said seats.

6. In an internal combustion engine having means forming a cylinder receiving portion, the combination of: cylinder head forming means having an annular seat positioned over the outer end of said portion; a cylinder mounted in said portion having an annular surface at one end for engaging said seat; and means adjacent the opposite end of said cylinder securing said cylinder on said seat.

7. In an internal combustion engine having means forming a cylinder receiving portion, the combination of: cylinder head forming means having an annular bevelled seat positioned over the outer end of said portion; cylinder forming means mounted in said portion, said means comprising a cylindrical wall bevelled at one end to form a surface for engaging said seat; and means securing said cylinder on its seat.

8. In an internal combustion engine having means forming a cylinder receiving portion, the combination of: cylinder head forming means having an annular bevelled seat positioned over the outer end of said portion; cylinder forming means mounted in said portion, said means comprising a cylindrical wall bevelled at one end to form a surface for engaging said seat; and means adjacent the opposite end of said cylinder securing the cylinder on its seat.

9. In an internal combustion engine of the opposed piston type: a pair of cylinders; means forming a frame having receiving portions respectively for said cylinders, there being an opening in said frame means adjacent the head ends of said cylinders; a closure for said opening, having a head forming portion insertible therethrough for interposition between said cylinders; means forming oppositely directed annular seats on said portion, seating surfaces respectively on the head ends of said cylinders; and means securing said cylinders with said surfaces respectively engaging said seats.

10. In an internal combustion engine having a pair of spaced parallel crank shafts and at least a pair of cylinder forming means extending toward each other respectively from said shafts

10 with their axes angularly displaced, and in end to end relation, said engine including frame forming means providing cylinder receiving portions for mounting said cylinder forming means: there being an opening in said frame forming means adjacent the head ends of said cylinders through which said cylinder forming means are optionally insertible and removable; means detachably securing said cylinder forming means respectively in said portions; and a demountable closure for said opening, including head forming means for said cylinders.

15 11. In an internal combustion engine having a pair of spaced parallel crank shafts and at least a pair of cylinder forming means extending toward each other respectively from said shafts with their axes angularly displaced, and in end to end relation, said engine including frame forming means providing cylinder receiving portions for mounting said cylinder forming means; there being an opening in said frame forming means adjacent the head ends of said cylinders through which said cylinder forming means are optionally insertible and removable; a demountable closure for said opening, including head forming means insertible through said opening to a position between the head ends of said cylinders; and means urging said cylinder forming means to seat against said head forming means.

20 12. In an internal combustion engine having a pair of spaced parallel crank shafts and at least a pair of cylinder forming means extending toward each other respectively from said shafts with their axes angularly displaced, and in end to end relation, said engine including frame forming means providing cylinder receiving portions for mounting said cylinder forming means: there being an opening in said frame forming means adjacent the head ends of said cylinders through which said cylinder forming means are optionally insertible and removable; a demountable closure for said opening, including head forming means insertible through said opening to a position between the head ends of said cylinders; and means respectively adjacent the ends of said cylinder forming means remote from said head ends urging said cylinder forming means to seat against said head forming means.

25 13. In an internal combustion engine having a pair of spaced parallel crank shafts and at least a pair of cylinder forming means extending toward each other respectively from said shafts with their axes angularly displaced, and in end to end relation, said engine including frame forming means providing cylinder receiving portions for mounting said cylinder forming means; there being an opening in said frame forming means adjacent the head ends of said cylinders through which said cylinder forming means are optionally insertible and removable; a demountable closure for said opening, including head forming means insertible through said opening to a position between the head ends of said cylinders; said means having a through opening for establishing communication between said cylinders; oppositely directed annular seats on said means extending about said opening; annular seating surfaces respectively on the head ends of said cylinders; and means urging said cylinders to cause said surfaces to engage said seats.

30 14. In an internal combustion engine having a pair of spaced parallel crank shafts and at least a pair of cylinder forming means extending toward each other respectively from said shafts

with their axes angularly displaced, and in end to end relation, said engine including frame forming means providing cylinder receiving portions for mounting said cylinder forming means: there being an opening in said frame forming means adjacent the head ends of said cylinders through which said cylinder forming means are optionally insertible and removable; a demountable closure for said opening, including head forming means insertible through said opening to a position between the head ends of said cylinders; said means having a through opening for establishing communication between said cylinders; oppositely directed bevelled annular seats on said means extending about said opening, said cylinders each comprising a cylindrical wall bevelled at its head end to form a seating surface; and means urging said cylinders to cause said surfaces to engage said seats.

15. In an internal combustion engine having a pair of spaced parallel crank shafts and at least a pair of cylinder forming means extending toward each other respectively from said shafts with their axes angularly displaced, and in end to end relation, said engine including frame forming means providing cylinder receiving portions for mounting said cylinder forming means: there being an opening in said frame forming means adjacent the head ends of said cylinders through which said cylinder forming means are optionally insertible and removable; a demountable closure for said opening, including head forming means insertible through said opening to a position between the head ends of said cylinders; said means having a through opening for establishing communication between said cylinders; oppositely directed bevelled annular seats on said means extending about said opening, said cylinders each comprising a cylindrical wall bevelled at its head end to form a seating surface; and means respectively adjacent the ends of said cylinders remote from said head end for securing said cylinders on said seats.

16. In an internal combustion engine having means forming a cylinder receiving portion, the combination of: cylinder head forming means having an annular seat over the outer end of said portion; a cylinder mounted in said portion having an annular surface at one end for engaging said seat, and an oppositely directed annular surface axially spaced therefrom; and means engaging said oppositely directed surface and secured to said portion for urging said cylinder toward said seat.

17. In an internal combustion engine having means forming a cylinder receiving portion, the combination of: cylinder head forming means having an annular seat over the outer end of said portion; a cylinder mounted in said portion having an annular surface at one end for engaging said seat; and means including a ring member coaxial with said cylinder and secured in said portion for securing said cylinder on said seat.

18. In an internal combustion engine having

means forming a cylinder receiving portion, the combination of: cylinder head forming means having an annular seat over the outer end of said portion; a cylinder mounted in said portion having an annular surface at one end for engaging said seat; and a cylindrical surface spaced therefrom for engaging in sealing relation a cylindrical surface in said portion; and means adjacent the opposite end of said cylinder securing said cylinder on said seat.

19. In an internal combustion engine having means forming a cylinder receiving portion, the combination of: cylinder head forming means having an annular seat over the outer end of said portion; a cylinder mounted in said portion having an annular surface at one end for engaging said seat; and a pair of axially spaced cylindrical surfaces spaced therefrom for respectively engaging in sealing relation, cooperating cylindrical surfaces in said portion, that cylindrical surface on said cylinder most remote from said annular surface being of less diameter than the other cylindrical surface on said cylinder, to facilitate removal of said cylinder through said outer end; and means adjacent the opposite end of said cylinder securing the cylinder on said seat.

20. In an internal combustion engine having means forming a cylinder receiving portion, the combination of: cylinder head forming means having an annular seat over the outer end of said portion; a cylinder mounted in said portion having an annular surface at one end for engaging said seat, said cylinder having a port opening through the wall thereof intermediate its ends; means forming axially spaced seals between said cylinder and said portion respectively on opposite sides of said port; and means adjacent the opposite end of said cylinder securing said cylinder on said seat.
